UNITED STATES PATENT OFFICE.

ALBERT D. BIGLER, OF CLEARFIELD, PENNSYLVANIA.

BRICK WALL CONSTRUCTION.

1,419,805.

Specification of Letters Patent. Patented June 13, 1922.

Application filed March 3, 1920. Serial No. 363,006.

To all whom it may concern:

Be it known that I, ALBERT D. BIGLER, a citizen of the United States, residing at Clearfield, in the county of Clearfield and 5 State of Pennsylvania, have invented new and useful Improvements in Brick Wall Construction, of which the following is a specification.

This invention relates to wall construction 10 and specifically to improvements in facing brick used in such structure.

My invention is applicable for use in the construction of building walls wherein the utmost stability and longevity are desired, 15 together with a pleasing and ornamental appearance, and in the construction of vaults and buildings where it is essential that the structure present no external mortar joints which may be readily attacked for the purpose 20 of destroying the wall.

The objects are to provide a brick which, when used in the construction of a wall, will be seated or locked by the binding mortar with the utmost security, which is so formed 25 as to protect the binding mortar from moisture and the elements, which, when placed together, form a unitary wall or structure presenting no external mortar seams, which will be fireproof and which, when placed in 30 position, present a highly ornamental appearance.

With the above and other objects in view, my invention consists in certain features of structure, combination and relation, and 35 which will be set forth more fully herein-after.

I have illustrated one embodiment of my invention in the accompanying drawings, wherein:

40 Figure 1 is a perspective view of a brick constructed in accordance with my invention.

Figure 2 is a side elevation of a portion of a wall constructed with my improved 45 brick and in accordance with the invention.

Figure 3 is a perspective view of a modified form of brick constructed in accordance with my invention.

Figure 4 is a side elevation of a portion 50 of a wall constructed with the modified form of brick illustrated in Figure 3.

Referring to the drawings, wherein similar numerals denote like parts throughout the several views:

55 Referring to Figures 1 and 2 of the drawings, I provide a brick generally designated

as 1. This brick may be of any general shape or form and has its front face beveled, as indicated at 2. The under side of the brick is recessed, as indicated at 3, so as to 60 provide a flat surface adapted to bear upon the binding mortar 4 and which forms, in conjunction with the beveled front face, a flange 5 which, in a wall construction, is adapted to overhang the front face of the 65 next lower brick, thereby making a tight joint, enclosing the mortar from the atmosphere, and providing, in addition to the horizontal binding surface 3 a concave and relatively vertical binding surface 6. 70

Referring to Figures 3 and 4 of the drawing which illustrate what I now consider to be the preferred embodiment of my invention, 7 designates a brick which may be provided with a central longitudinal channel, as 75 indicated at 8. The front face of the brick is beveled, as at 9, and has a cut-away portion 10 adjacent the top thereof. The bottom of this modified form of brick is recessed so as to provide a relatively flat binding surface 11 and a flanged portion 12, which flanged portion has an inner beveled face, as at 13, so formed as to cooperate with the beveled top portion of the next lower brick in order to form a tight joint. 80

The improved block in its two forms transversely increases in thickness from the upper portion downwardly and outwardly towards the front thereof, the rear side of each block being vertically straight. The 90 front face of each block is also downwardly and outwardly inclined to the lower edge of the projection. This increase in transverse thickness towards the bottom of the block gives the latter a stable setting and 95 materially aids in holding the lower depending front projection of each block firmly applied when introduced into or made a component of a wall structure. There is no cement or mortar introduced between the 100 projection and the portion of the block below which it engages and overhangs either in the first or second form of the block, the interposed cement or mortar all being confined in the recess in rear of the projection 105 to effect a more positive setting of each block and a more expeditious front finish. Moreover, all joints between the blocks are concealed, and the overlap of the projections without a cement or mortar binding between 110 the same and the adjacent portion of the lower block will obviate water or moisture

passing upwardly or seeping through the mortar or cement binding in the rear of each projection. The downward and outward inclination of the front face of each 5 block provides for the formation of a wall which will advantageously shed water and prevent lodgment of moisture at the joints which are shielded or fully covered.

Having described my invention, what I 10 claim is:

1. A building block having a depending projection at its outer lower side portion extending the full length of the block and constituting the lower front terminal of the 15 same, the block being provided with a bottom recess from the rear side of the block to and continuing into the rear side of the projection, the wall of the said bottom recess being straight and continuing into the rear 20 side of the projection by a curved wall to permit the projection to fit over the upper portion of a corresponding block and provide a reduced extent of space between the bottom and top portions of adjacent blocks, 25 the space in the bottom of the block providing for a filling of cementitious material fully over the bottom of the block to the rear side of the projection, the block gradually increasing in transverse thickness from 30 the upper portion towards the bottom there-

of and the front face of the block having a straight slope downwardly and outwardly from the upper portion fully through the projection.

2. A building block having a rear vertically straight side, a flat top, a front lower depending projection constituting the lower front terminal of the block, and an upper downwardly beveled corner portion at the front, the front side of the block being 40 smooth and sloping downwardly and outwardly from the lower terminal of the upper bevel to the lower terminal of the projection, a recess being formed in the bottom of the block from the rear straight side of the 45 block to and continuing into a beveled rear side of the projection, the beveled rear side of the projection being adapted to snugly fit over the upper bevel of an adjacent similar block and the space providing means for a 50 filling of cementitious material between the bottom and upper sides of adjacent blocks.

In testimony whereof I have hereunto set my hand in presence of two subscribing witnesses.

ALBERT D. BIGLER.
